UNITED STATES PATENT OFFICE

168,669

AWNING OR SIMILAR ARTICLE

Clarence J. Berini, Farmington, Mich., assignor
of fifty per cent to Willis B. Anderson, Detroit,
Mich.

Application May 9, 1949, Serial No. 2,535

Term of patent 14 years

(Cl. D21—6)

To all whom it may concern:

Be it known that I, Clarence J. Berini, a citizen of the United States, residing at Farmington, county of Oakland, State of Michigan, have invented a new, original, and ornamental Design for an Awning or Similar Article, of which the following is a specification, reference being had to the accompanying drawing forming a part thereof.

Fig. 1 is a front perspective view of an awning or similar article, showing my new design.

Fig. 2 is an end elevational view thereof; and

Fig. 3 is a detail view to a large scale of a portion of the awning illustrating the configuration thereof.

The end of the awning not shown has substantially the same appearance as the end shown in Fig. 2.

The drawing figures are shaded to indicate color contrast.

The characteristic features of my design reside in the portions shown by means of full lines in the drawing.

I claim:

The ornamental design for an awning or similar article, substantially as shown and described.
CLARENCE J. BERINI.
